UNITED STATES PATENT OFFICE

2,315,727

COMMUNICATION SYSTEM

Harry J. Nichols, Point Pleasant, N. J., assignor
 to ~~International~~ Business Machines Corporation, New York, N. Y., a corporation of New York

Original application August 17, 1940, Serial No. 353,114. Divided and this application June 13, 1941, Serial No. 397,851

10 Claims. (Cl. 178—27)

The present invention is a division of applicant's copending application Serial No. 353,114, filed August 17, 1940 relating to interoffice or interstation communication systems and more particularly to communication systems for interconnecting separate typewriters of a certain standard construction, wherein the operation of any one typewriter, in a normal manner, can be either isolated, at will, from the operation of the system, to permit ordinary individual operation of the typewriters or, on the other hand, operation of one typewriter in the normal manner can be utilized to produce a copy, at a sending station, of the intelligence to be transmitted, and to simultaneously operate a second or receiving similar typewriter or a plurality of such receiving typewriters at remote points. In like manner, each of the plurality of receiving typewriters can be utilized when desired, as sending typewriters, and means are provided for "break-in" by a receive station, so that the direction of transmission can be reversed when necessary or desired.

In devices of the prior art wherein interoffice messages have been transmitted, special machines, which are not the usual standard equipment of business offices, have been employed. There have also been previously provided, electrical interconnecting systems for standard typewriters, but such systems have required either an extensive modification of the mechanical structure of the typewriter itself, to adapt it to such a system, or have required complicated mechanical permutation bar devices for translating a received signal, in order to produce selective actuation of a character key bar in accordance with the signal received.

Accordingly, one of the objects of the present invention is to provide novel means for interconnecting and operating two or more standard office equipment typewriters, such as the well known "Electromatic" typewriter, so that such a standard instrument is utilized with very little additional equipment, in an interoffice communication system, to produce speedy and accurate transmission and reception of messages.

A further object is to provide a system of communication for interconnecting at least two standard office typewriters, comprising means controlled by each depressed key of the keyboard for setting up, in a simple and direct manner, a code combination of signal impulses representative of the function or character associated with the depressed key, and including start and stop signal impulses, said code combination comprising a plurality of electrical impulses of identical

characteristics and of equal duration, a single signal channel for interconnecting the typewriters, means for transmitting selectively and sequentially through said channel the individual elements or impulses of a signal, representing a particular function or character, and a novel combined mechanical-electrical translator controlled by the selecting elements of the code combination, for selectively energizing, at a standard receiving typewriter, solely the operating solenoid of the key bar corresponding to the key depressed at the sending station, for operating said corresponding key bar, whereby the depression of a chosen character key of a standard typewriter at one station produces the typing of the selected character at a remote station by means of a similar standard typewriter.

Still another object is to provide a system of interoffice or interstation communication including at least a pair of standard office typewriters having a modified keyboard, a series of solenoids, one for each character key, means controlled by a selected character key for producing a combination of signal code elements representative of the character, means for interconnecting the respective typewriter solenoids including one signal channel only, over which the code signal elements representative of said character are sequentially transmitted, start-stop, send-receive distributor means for sending or receiving, respectively, at separate stations, and in synchronism, the code elements comprising a representative signal, and novel mechanical-electrical translator means for receiving said code elements, translating the same, and selectively choosing that solenoid only, which corresponds to the key depressed at the sending station.

Still another object is to provide a novel positive type mechanical translator.

A further object is to provide a novel mechanical-electrical translator for receiving the characteristic code signal elements and selectively choosing the corresponding character solenoid.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a schematic view illustrating teleprinting devices such as office typewriters suitable for ordinary office work and also utilized for producing code signal permutations representative of a character and controllable by remotely

originating signals, to type a character, and means for electrically interconnecting a pair of such devices by a minimum number of signal channels for signal transmission therebetween.

Fig. 2 is a schematic view, in skeleton outline only, illustrating fundamentally how the operation of a character key produces a code permutation of signal components representative of the particular character, which components, in turn, are relayed in seriatim, to the line, by a distributor assembly, and also illustrating how a corresponding key bar is electrically operated, by a characteristic signal received from a remote station and translated, to thereby select the corresponding solenoid.

Fig. 3 is a schematic diagram illustrating in outline only, a complete communication system including separate sending and receiving stations, respectively, and the circuits for "break in."

Fig. 36 is a perspective view of the shift and carriage release operating and signaling mechanism.

Referring to the drawings wherein like reference characters refer to like parts throughout the several views and more particularly to Fig. 1, the invention is illustrated in the present example as applied to a pair of standard "Electromatic" typewriters A and B at the sending station A and the receiving station B, respectively, but it is to be expressly understood that any type of standard office typewriter can be utilized in the novel combination of the present invention and that any number of typewriters can be so interconnected.

Typewriter A comprises an "Electromatic" typewriter provided with a standard keyboard wherein the typebars are power actuated, in a well known manner, upon depression of a chosen

character key and wherein a blank key SRK1, controls a send-receive relay (Fig. 3), as will be described in detail later.

Upon depression of any chosen character key, the character is typed on the record sheet 50 at station A and a novel composing permutation unit illustrated schematically in Fig. 2 is conditioned, as will be described later, so that a distinctive electrical signal is produced, composed of a predetermined permutation of similar electrical components, which components, by means of a distributor assembly including novel start-stop single revolution clutch mechanism, send-receive and line relays, respectively, are transmitted sequentially over the line to the typewriter B at the receive station. The respective components, when received at station B, are utilized to produce sequential conditioning of a shuttle magnet (Figs. 7 and 17) controlling a novel translator mechanism, as will be explained in detail later, whereby the tumblers of the translator are operated to adjust the cascade switch tongues of the translator to thereby choose, one certain key solenoid, similar to KS (Figs. 2 and 7) at the station receiving the signal, which key solenoid corresponds to the character key depressed at the send station. Energization of the corresponding solenoid will, through its connecting spring CS, depress the corresponding character key (Fig. 2) at the receive station B, so that the same character is typed on the record sheet 50 (Fig. 1) at both the send and receive stations. Similarly, any of the letters can be typed and any function can be performed, so that any message can be typed at station A and signals set up at station A, which when transmitted to station B, will type the same message on the machine at that station.

When the operator at station A wishes to send a message to station B, to be simultaneously typed upon both machines, the operator at station A, depresses the blank key SRK1, thereby conditioning the machine at station A for sending, station B being normally in receive condition, all as will be described in detail later. Warning and other signaling means may be provided between stations, in a manner well known in the art, but such warning and signaling means do not constitute any part of the present invention.

Referring specifically to Fig. 2, there is illustrated in skeleton outline only, the mechanism and circuits for the operation of a chosen character key at station A with the consequent mechanical typing of the selected character at station A and the setting up of means for producing a signal representative of the character, whereby such a signal is transmitted to station B to produce typing of the same character at said station. The operation of the send conditioned machine to produce a signal for remote operation of a receive conditioned machine is as follows: Upon depression of a chosen character key 51, the key bar 52 is oscillated about its pivot pin 53 against the force of return spring 54 to move an extension arm 55 downwardly. Upon such downward movement, the bifurcated lower end of arm 55 engages a pin 56 on arm 57 integral with the stop lever 58, to thereby rotate stop lever 58 counterclockwise about its pivot 59. This rotation disengages the channel shaped lug 60 of stop lever 58 from the right hand one of a pair of detents 61 on cam 62. An impeller arm 63, in contact with an impeller lug 64 on cam 62 is constantly urged in a clockwise direction by means of a spring 65 and upon the disengagement of a channel shaped lug 60 of the stop lever from a detent

61 of the cam, the impeller arm 63, by means of its contact with impeller lug 64, rotates the cam 62, slightly in a clockwise direction, until it engages the constantly rotating power roller 66 which is rotated about the stationary shaft 67 by means of the typewriter motor (not shown), in a manner well known in the art. The cam 62 by means of its engagement with power roller 66 is thereupon rotated a full half revolution clockwise, until the other detent 61, of the pair of detents on cam 62, engages the channel shaped lug 60 of stop lever 58, in a well known manner. Cam 62 is pivotally mounted by its axis 68 upon an arm 69 of a bell crank 70 which in turn is mounted for oscillation about a pivot 71, and upon such rotation of cam 62, its eccentric contour causes a lateral movement of the cam axis 68 to thereby oscillate bell crank 70 in a counter-clockwise direction. Such oscillation causes a downward movement of the arm 69a of bell crank 70 to pull down a link 72, to rotate bell crank 73 against the force of spring 74 to actuate link 75 to oscillate bell crank 76 to in turn actuate the typebar 77 to strike one of the type characters 78 against the record 50 (Fig. 1) in a manner well known in the art.

Also upon the rotation of cam 62 and consequent lateral movement of the cam axis, a roller 79 carried by the lower end of arm 69, is moved laterally to the right, as viewed in Fig. 2. Roller 79 is in engagement with a shoulder 80s on a permutation slider 80 mounted on suitable slotted guide bars 81 secured to the frame (not shown) of the typewriter unit. Each slider is provided with spaced studs 82 extending outwardly and alternately from one side and the other of the slider and such studs are carried on both the top and bottom horizontal bars 80t and 80b, respectively, of the slider member. Rotatably mounted on each of a plurality of code rockshafts 83, and alternately on opposite sides of the sliders, are the diagrammatically represented rockshaft actuating clips 84. These clips 84 are removably attached to the rockshafts, as described in detail later, the relative number and disposition of the clips in the assembly for each slider being dependent upon the particular code value of the character whose character key controls the respective slider member. Therefore, upon depression of any chosen character key, the respective code rockshafts 83, to which the clips are attached, will be rotated, as described presently, and in such a direction that the particular code permutation representing the character, will be set up by the respective permutation switches. It is to be particularly noted, that the universal bail rockshaft 83UB is always actuated by means of a clip 84 to permit its controlled contacts to move momentarily out of engagement to thereby produce a spacing condition on the signal channel, this rockshaft 83UB being diagrammatically illustrated as spring biased by means of a coil spring 85 acting through its associated clip 84 so that the rockshaft and slider 80 are returned to their original positions upon completion of the half revolution of cam 62.

Upon the above described lateral movement of the cam axis, the roller 79 moves the slider 80 to the right against the spring bias effect of spring 85 acting through clip 84 and its cooperating stud, 70 whereby the studs carried by the slider actuate the associated clips and rotate the universal bail rockshaft 83UB and such code rockshafts 83, as is required to set up the particular signal. Such actuation of the clips rotates the associated rockshafts to actuate the diagrammatically repre-

sented switch operating elements 86UB and 86 to permit the associated switch arm or tongue 87UX of the universal bail rockshaft to move out of engagement with its associated switch arm 87UXa and to move the associated switch arms or tongues 87 of the code rockshafts selectively into engagement with the associated switch arms 87a, dependent upon the direction of rotation of the code rockshafts, respectively. It is to be particularly noted, that all code permutation signal settings are differentially produced and only those rockshafts are actuated, which require a change from the setting for the previously typed character. If the same letter is typed twice in succession, the corresponding slider is twice actuated, but only the universal bail rockshaft is rotated since the remaining rockshafts remain in their previously set position, as described in detail later. Thus, such permutation switch elements 87a and 87 as are moved into engagement, close a circuit from the positive side of a D. C. source B1, as illustrated diagrammatically in Fig. 2 and the universal bail likewise opens a circuit to the positive side of the same source by separation of its pair of contacts 87UX and 87UXa, in series, with a pair of relay controlled contacts 88 and 88a, between the positive side of said source and the distributor assembly.

The particular permutation of switches closed will thereby supply positive potential to the distributor assembly, including the novel start-stop single revolution clutch mechanism, send-receive relay and line relay, diagrammatically illustrated only, in Fig. 2, which, in turn, at the proper time and in proper sequence will transmit the code signals through the signal channel represented by the line, to the distributor assembly at the receive station, in a manner to be described in detail later. Upon completion of a full half revolution of the cam 62, the universal bail rockshaft 83UB is returned to its normal position by spring 85, thereby producing closure of contacts 87UX and 87UXa but the code rockshafts 83 are retained in their actuated positions by coacting detent pins, as described later, until depression of another character key bar. It is seen, therefore, that in a simple and direct manner, a standard office typewriter, such as the "Electromatic" typewriter can be utilized, to locally type a character and to set up a code signal having a desired permutation of components, characteristic of the selected character, which signal may be transmitted over the signal channel represented by the line, by the novel means now to be described and which may be utilized at a remote typewriter to type the same character.

The novel communication system comprising the present invention consists of novel permutation means at each station for composing or setting up a series of code signals representative of the characters to be remotely typed, a novel distributor assembly, comprising in addition to a send-receive relay and a line relay, novel distributor mechanism and a start-stop single revolution clutch mechanism, controlled by the line relay, to in turn control the operation of the distributor mechanism at the same station. The code signal set up by the permutation unit is sequentially transmitted, by the sending distributor to maintain synchronism between the distributor mechanisms at the local station and at the remote stations and to produce typing of the desired character or performance of the desired function, the remote distributor mechanism controlling novel translator means utilizing the signal elements re-

ceived to thereby operate that solenoid only, corresponding to the character key depressed at the sending station.

A general description coordinated by reference 5 to the respective figures of the drawings, will first be given, of the essential elements of a complete communication system and then a detailed description of the sending or transmitting mechanism and circuits and of the receiving mechanism and circuits including a detailed description 10 of the respective component elements of these mechanisms and circuits will be given, which will be followed by a detailed description of the operation of the system including transmission, reception, break-in and other communication functions.

General description

A plurality of typewriters, such as the machine at station A and the machine at station B (Fig. 20) with their respective associated electrical elements, distributor assembly including start-stop mechanism and various control elements are interconnected to comprise the novel teleprinting communication system. The system operates on 25 the start-stop, Baudot 6-unit code principle, and by means of associated circuits and mechanisms, two-way transmission of messages over a single channel is provided.

Novel permutation mechanism, as shown in 30 detail in Figs. 8 to 14, inclusive, controlled in the manner as diagrammatically illustrated in Fig. 2, is utilized to open the line circuit to produce the start signal, to set up a code signal of separate signal components, characteristic of the character represented by the chosen depressed key and to produce a stop signal. The particular permutation switch elements which are placed in a closed circuit relation by the permutation mechanism close a circuit up to contacts, as 35 shown in Fig. 4, which contacts are sequentially controlled, by the transmitting distributor cams which are mounted on the start-stop shaft along with the receive cams and control cams.

Upon depression of a chosen character key 40 bar to thereby locally type the character and simultaneously set up the code signal representative of that character, the universal bail contacts are operated to open the line circuit and thereby release the novel clutch and start-stop mechanisms of Figs. 25 and 26 or of Figs. 27-35, inclusive, whereby the start-stop shaft is rotated one complete revolution, only, and the code signal set up by the permutation unit is sequentially transmitted to the line by means of the distributor cams and the send-receive relay, as diagrammatically illustrated in Fig. 4. The line signals received at the distributor assembly of typewriter B (Fig. 1) control a shuttle magnet (Figs. 7 and 17) to position selectively the tumblers of the novel selector mechanism of Figs. 15, 17, 18 and 22 or of the novel selector mechanism of Figs. 23 and 24, which tumblers selectively set the cascade switch elements of the translator, as illustrated in Fig. 7, so that the particular key solenoid KS only, which corresponds to the chosen character, is energized, thereby (Fig. 2) pulling down the key bar of the chosen character key at station B (Fig. 1) and producing remote typing of the chosen character.

Transmitting mechanism

The transmitting mechanism comprises a novel permutation unit controlled by the key bars of the transmitting typewriter, which permutation unit controls circuits leading to con-

tacts controlled by transmitting cams of the distributor mechanism. The circuits closed by the transmitting distributor cams transmit code elements of the signal to a send-receive relay at the send station which relay controls the transmission of the signal elements through a line relay at the sending station and to a line relay at the receiving station. The line relay at the sending station, controls the operation of a novel start-stop single revolution clutch mechanism which, in turn, controls the operation of the distributor mechanism. The construction of the permutation unit, the transmitting distributor unit of the distributor assembly, the several start-stop single revolution clutch mechanism modifications and the shift and carriage release mechanisms will now be described in detail.

Referring to Figs. 3 to 14, inclusive, there is disclosed therein details of the elements comprising the novel permutation unit and the manner of assembly thereof. In Fig. 3 is illustrated the manner of mounting the several code rockshafts and the universal bail rockshaft. Each of the code rockshafts 83 comprises a cylindrical element, axially bored at each end to form openings 83a into which project the pivot screws 89, each mounted in a support plate 89a, thereby rotatably supporting the individual rockshafts. Each rockshaft 83 is provided with a plurality of pairs of slots 83s. As shown in Figs. 10 and 11, a plurality of rockshaft operating clips 84 are detachably mounted on the individual rockshafts by insertion of the legs 84a and 84b of the clips into the respective slots comprising each pair. The rounded end 84c on the leg 84b of each clip locks the clip to the rockshaft after insertion thereof into the slots. Each clip is provided with an offset 84d (Fig. 11) so that the clips can be mounted to cooperate with either the lugs 82 on one side of the slider or with the lugs on the opposite side of the slider, as is seen in Fig. 11. Further, the clips are mounted on the respective shafts either in upright or in inverted position, as is illustrated in Fig. 10 and as diagrammatically indicated in Fig. 2. The particular arrangement and position of the clips for each slider is determined by the particular code value of the character or function whose key controls the slider. It is to be particularly noted, that as certain of the pairs of contacts controlled by the code rockshafts, are closed, others are simultaneously opened, so that only those pairs of contacts corresponding to the code value of the particular character or function, remain closed, as the slider 80 (Fig. 2) returns to its original position under the control of the torque bias spring 85. Mounted on both the top and bottom bars 80t and 80b, respectively, of the slider 80, are the studs 82 attached alternately to opposite sides of the respective bars, as illustrated in Figs. 10 and 11. The single elongated arm of the clips 84 abuts these lugs, in one position of the rockshafts, so that upon lateral movement of the slider 80, to the right as viewed in Fig. 10, certain of the code rockshafts are rotated clockwise by the upwardly directed, single elongated arms of the clips, respectively, and the remaining code rockshafts are rotated counterclockwise by the downwardly directed single elongated arms. It is assumed, merely for purposes of clarity in description, that such clockwise rotation produces separation of the control contacts while counterclockwise rotation moves the contacts into engagement.

Each code rockshaft is further provided with 75

an axially extending elongated notch 83b formed in the outer periphery of the rockshaft at one end thereof, and with a shorter axially extending notch 83c, formed in the outer periphery of the rockshaft, at the opposite end thereof, as illustrated in Fig. 9.

The universal bail rockshaft 83UB (Fig. 8) is provided with a portion of reduced diameter 83rd at one end, extending axially of the shaft and a slot 83s, extending axially of the shaft, is formed in the outer periphery of this reduced portion. A coil bias spring 85 is slipped over the reduced portion before the shaft is mounted on its supporting pivot screws 89. One end of the coil spring terminates in a portion 85a, extending radially inwards, which is fitted into the axially extending slot 83s, as the coil spring is slid into position over the reduced portion 83rd. The opposite end of the coil spring 85 comprises a radially extending portion 85b which extends laterally to the right, as viewed in Fig. 8, and under the pivot screw 89 of the adjacent code rockshaft. By rotating the universal bail rockshaft before the clips are inserted and then inserting the clips to hold the coil spring in its coiled position, an adjustable amount of torque can be produced by the universal bail rockshaft and spring assembly so that the rockshaft contacts are positively closed with a desired force by the spring bias of the universal bail rockshaft upon release of the associated slider 80 by the roller 79 (Fig. 2).

In Figs. 12, 13 and 14 are illustrated the assembly and coaction of the code rockshafts, notches, contact actuating push pins, contacts and detent pins. A permutation switch actuating element or push pin 86 (Fig. 12) having an insulated end 86a is mounted for vertical movement, as viewed in Fig. 12, in openings 90b and 90a in the support and guide plates 91 and 92, respectively, the uninsulated lower end of the push pin fitting into the axially extending notch 83b in a code rockshaft 83 or in the universal bail rockshaft, while the insulated end abuts the self, spring biased blade contact 87 held in spaced relation from the cooperating blade contact 87a, by well known insulating support means 93. In Fig. 12, the push pin is shown as entered in the elongated axially extending notch 83b so that the lower blade contact 87 is out of engagement with the cooperating blade 87a. In Fig. 13, the push pin 86 is shown in its actuated position which position is assumed upon counterclockwise rotation of the rockshaft whereby the lower end of the push pin is forced out of the notch 83b and onto the regular outer periphery of the rockshaft whereby the push pin is thereby moved bodily upwards, carrying the lower contact 87 into engagement with contact 87a.

In Fig. 14, are illustrated the relative positions of the detent pin and the axial slot at the outer end of the rockshaft 83. As is seen in Fig. 9, the longer axially extending notch, cooperating with the push pin, is spaced circumferentially about the periphery of the code rockshaft with respect to the shorter slot on the opposite end of the shaft, which shorter slot cooperates with the detent pin. As the rockshaft is rotated counterclockwise, as viewed in Figs. 12 and 13, the notch 83b assumes the position of Fig. 13 while the notch 83c assumes the position of 83b in Fig. 12. A detent pin 94 having a flanged portion 94a integral therewith is mounted for vertical movement in the openings 95a and 95b in the support and guide plates 96 and 97, respectively. A coil spring 98 abuts the support plate 96 at one end

thereof and exerts a downward force upon the flanged portion 94a thereby urging the flange towards the guide plate 97 and holding the lower end of the detent pin in the notch 83c, as is seen in Fig. 14. It is seen, therefore, that upon rotation of a shaft 83, the notch 83b is moved out of engagement with the cooperating push pin 86 and the outer periphery of the rockshaft is moved into engagement with the push pin to thereby move the pin vertically, while the notch 83c is aligned, upon such rotation, with the spring bias detent pin 94 which pin 94 enters notch 83c as shown in Fig. 12 and the rockshaft is therefore positively held in its rotated position until forced back to its initial position by a slider actuated clip.

The operation of the permutation unit is as follows: Upon lateral movement to the right, for example, of the slider 80 as viewed in Fig. 2, the slider and its studs 82 are moved to the right. Such movement actuates the clips 84 to rotate the respective code rockshafts either clockwise or counterclockwise depending upon the particular assembly of the clips for the actuated slider. Counterclockwise rotation of certain of the code rockshafts, produces closures of the cooperating contacts controlled thereby while clockwise rotation of the other rockshafts permits the cooperating contacts to open. As certain of the rockshafts are rotated counterclockwise to thereby close the associated contacts (Fig. 13) the associated detent pin is aligned with a slot 83c (Fig. 14) and the end of the spring urged detent pin enters the slot to positively hold the rockshaft in its new, contact closing position. As other rockshafts are rotated clockwise, the notches 83c are moved out of alignment with the associated detent pins and the shafts assume the position as shown in Fig. 12 with the contacts 87 and 87a out of engagement. The contact operating pins engaging with their respective notches now serve in the same capacity as did the detent pins in the prior positions of the rockshafts. A certain desired permutation of the pairs of contacts remains closed after slider 80 moves back to its initial position under the bias of the torque spring 85.

The universal bail rockshaft 83UB is rotated against the torque exerted by coil spring 85, by means of its clip 84 and associated lug 82 upon lateral movement of any slider 80, to the right, to thereby open its associated contacts 87UX, 87UXa (Fig. 2) and momentarily open the line, as will be explained in detail later. Upon the return of slider 80 to its initial position, the spring 85 of the universal bail rockshaft rotates the rockshaft back to its initial position to thereby close its associated contacts 87UX and 87UXa. It is to be noted that no detent pin and cooperating slot is provided for the universal bail rockshaft.

Upon the closure of any pairs of contacts 87, 87a, a circuit is closed (Fig. 4) to the contacts controlled by the cams of the translation distributor unit of the send-receive mechanism, which mechanism will now be described in detail.

Referring to Figs. 15, 16, 17 and 19, the construction, assembly and operation of the distributor of the send-receive mechanism are illustrated therein. A plurality of transmission cams T1 to T6, inclusive and control cams TC, TL and TP are mounted on the start-stop shaft 99 in position to be lubricated by oiler wicks OW (Fig. 16) along with the receive cams described later. Control cam TC controls contacts (Fig. 4) which, in turn, control the circuits of the control magnet, control cam TL (Fig. 6) controls the contacts

which, in turn, control the circuit to a latch magnet. Transmission cams T1 to T6, inclusive, (Fig. 4) control contacts connected in series between the permutation unit contacts and the send-receive relay while cams T4, T5 and T6 also control holding circuits (Fig. 7) for group magnets of the translator. Transmission cam TP (Fig. 7) controls contacts which, in turn, control the circuit providing energization of the particular key solenoid selected by the translator in response to a received code signal and also controls holding circuits for the group relays.

Referring to Figs. 15 and 17, the horizontal start-stop shaft 99 is transversely journaled in ball bearings 100 forced into suitable recesses bored in the vertical side plates 101 of the distributor mechanism. The start-stop shaft is intermittently driven by means of a novel start-stop single revolution clutch mechanism 102 (described later) which is controlled by a start-stop magnet assembly SSM. When the universal bail opens the line circuit, as described above, the magnet SSM is deenergized to thereby release the stop arm 103 (Fig. 17). This release of the stop arm allows a spring 103s to rotate the arm 103 counterclockwise, so that a pawl 104 (Fig. 15) attached to the stop arm 103 is moved out of the path of rotation of the stop pin 104B attached to a member of the start-stop clutch and into the path of stop pin 104A intercepting said stop pin to thereby arrest the rotation of the start-stop clutch to halt the start-stop shaft in the preliminary stop position. When the start-stop magnet SSM is subsequently energized, the stop arm 103 is moved clockwise (Fig. 17) into the path of rotation of the stop pin 104B to thereby stop the start-stop shaft in the second or normal stop position.

The send or transmitting cam sleeve 106 is attached in any well known manner, such as by means of a set screw 106a, to the start-stop shaft 99 for rotation therewith. The cams TC, TL, T1 to T6, inclusive, and TP are fixed in a chosen sequence on the shaft 99, the separate cams cooperating with their respective push pins to actuate the associated contacts, as described above, and the separate cams being maintained in proper relative axial position by means of spacer rings 107. The cams are clamped against the flange 106f at one end of the transmitting cam sleeve by means of the receive cam sleeve 108 urged against the right hand spacer ring 107 cooperating with cam TP by means of the thrust exerted by a nut 99b threaded on the right hand end 99a of the start-stop shaft 99. A key way 109 is machined in the outer periphery of the cam sleeve 106 into which is positioned a cylindrical key 110 coacting with the inner periphery of the cams to lock the cams and cam sleeve together for simultaneous rotation by means of the start-stop shaft. The contacts controlled by the respective cams are diagrammatically illustrated in Figs. 4 and 7, it being particularly noted that these contacts are controlled by means of the push pins and that the relative positions of the cams, push pins and contacts are as illustrated in Fig. 15. The particular, circumferentially extending, sequence of the cams and their position relative to the respective push pins 111 is illustrated schematically in Fig. 19.

Referring to Figs. 15 and 16, the hardened steel push pins 111 provided with insulated ends 111a are aligned with the respective cams by insertion into openings in the front contact mounting plate 112 and in the back contact mounting plate 113

fastened by screws 114a to the mounting block 114 attached to the base panel 115 by screws 115a. Upon rotation of the start-stop shaft 99, the rounded ends 111b of the steel push pins 111, cooperating with the respective cams, sequentially make and break the associated transmission contacts, as will be clear from Fig. 16, to thereby transmit to the line, the elements of a particular code signal, as set by the permutation switches P1 to P6, inclusive, each comprising a pair of contacts 87 and 87a.

Referring to Figs. 3, 15 and 16, it is seen that cam TC controls the three contacts 211, 212 and 213 comprising switch TXC, cam TL (Figs. 7 and 15) controls the five contacts 221, 222, 223, 224 and 225 comprising the switch TXL, cams T1 to T3, inclusive, control the respective pairs of contacts comprising switches TX1, TX2 and TX3, respectively (Figs. 7 and 15), cams T4 to T6, inclusive, and cam TP, each controls the four contacts comprising the switches TX4, TX5, TX6 and TXP, respectively (Figs. 7 and 15). The contact assemblies comprising the respective switches are secured to the front and back plates 112 and 113, respectively, (Fig. 17) by means of screws 116 (Fig. 17).

The details of one form of start-stop and single revolution clutch mechanism 102, which is an improvement of the start-stop clutch of the copending application of Harry J. Nichols and Henry Tholstrup, Serial No. 353,113 filed August 17, 1940 and comprising generally an over-riding roller type clutch in which six small rollers coasting with a spider and driver cup engage by means of wedged action to produce a positive drive, all as disclosed in applicant's copending application Ser. No. 397,852, filed June 13, 1941, is illustrated in detail in Figs. 25 and 26.

The clutch mechanism as illustrated in Fig. 27 is generally of the same construction as that illustrated in Figs. 25 and 26, with the exception that a single stop pin is provided on the controller ring of the drive of Fig. 27 and a rebound cam is also provided. Since the constructions are generally the same, the description of Fig. 27 will clarify the construction of both types. Referring to Fig. 27, the respective parts of the clutch of Figs. 15, 17 and 25 (with the exception of the double stop pins) are shown in detail. The clutch 102 (see also Figs. 15 and 17) comprises a driving collar 116 fastened to a motor drive shaft 117 (Fig. 25) by a set screw 118. The driving collar 116 is provided with a plurality of driving pins 119 received in holes 119a (Fig. 25) formed in the driver cup 120, mounted for rotation on start-stop shaft 99. Oiler wicks (not shown) are inserted in radial openings 120a in the driver cup, their inner ends touching the shaft 99 and thereby insuring lubrication between the driver cup and the shaft. A retainer ring 120b (Fig. 29) is slipped over a reduced circumference of the driver cup to hold the oiler wicks in place. A steel ball 121 (Figs. 25 and 29) is inserted in conical shaped depressions in the ends of the motor drive shaft 117 and of the start-stop shaft 99 to provide alignment between these shafts. Such a construction allows the two shafts to be easily aligned. The driving rollers 122 are jointly controlled by a notched disk or cage 123 and a controller ring 124, which ring is rotatably mounted on a hub 125a of a spider 125 and is provided with a torque spring 126 having one end inserted into an opening 126a in the controller ring and the other end in opening 126b in a separator disk 127. The rollers 122 are fitted at one end thereof into notches 123a formed in the

cage 123 and the opposite ends thereof are inserted into openings in ring 124. A plurality of circumferentially extending elongated eccentric notches 124a are formed in the spider 125. The spring 126 tends to rotate the controller ring 124 so that the rollers 122 are urged towards the shallow part of the notches or the engaging position of the clutch. The cage 123 is in frictional engagement with a washer 128 which in turn is urged into engagement with the cage by a cup shaped spring washer 129 bearing on the bottom of the cup 120, so that a force is always exerted upon the cage 123 by the rotation of the driver cup 120.

In the embodiment as illustrated in Figs. 25 and 26, the controller ring is provided with a pair of stop pins 104A and 104B cooperating with a lug 104 on the arm 103 controlled by the armature of the start-stop magnet SSM (Figs. 15 and 17). Engagement of the lug 104 with either the pin 104A or 104B, holds the controller ring 124 against the force of the torque exerting spring 126 so that the rollers 122 are held out of the interlocking engagement between the rollers, the driver cup and the spider, all as explained in detail in the copending application of Harry J. Nichols and Henry Tholstrup, above mentioned. The spider 125, in this embodiment, is connected to the start-stop shaft 99 by means of a taper pin 130, passing through the retainer collar 131 integral with the separator ring 127, and into shaft 99. As illustrated in Fig. 26, the cage 123 positions the rollers 122 out of engagement with the spider 125 and the driver cup 120 so that under this condition the controller ring 124 is held from rotation by engagement between one of the stop pins and the lug 104.

Referring to the embodiment as illustrated in Figs. 27, 28 and 29, the controller ring 124 is provided with a single stop pin 104SP, only, but by means of a novel single revolution mechanism, as illustrated in Figs. 30 to 35, inclusive, as described in detail later, the start-stop clutch mechanism of Figs. 27 to 35, inclusive, can be utilized to replace the start-stop clutch of Figs. 25 and 26 with its associated mechanism, as illustrated in Figs. 15 and 17. Also in the embodiment of the clutch mechanism, as illustrated in Figs. 27 to 29, inclusive, the cotter pin or taper pin 130 passes through a rebound cam 131c instead of through the retainer collar 131 of Fig. 25. The rebound cam 131c cooperates with a rebound lever 132, as will be explained in detail later. An opening 126c is provided in the rebound cam 131c, which opening is aligned with the similar opening in the separator ring 127, the end of the torque spring passing through the separator ring and into the rebound cam, as illustrated in Fig. 29.

The operation of the novel start-stop single revolution mechanism of Figs. 25 and 26 is as follows: Upon receipt of a start signal, the start-stop magnet SSM (Fig. 17) is deenergized and the spring 103s moves the armature SSMA away from the magnet SSM and thereby rotates the start-stop arm 103 counterclockwise so that the lug 104 is moved out of the path of rotation of the pin 104B and into the path of rotation of pin 104A thereby stopping the clutch in the preliminary stop position, upon engagement of pin 104A and lug 104. This is the position of the clutch when the system is deenergized and is not in use. Upon depression of the send-receive key SRK1 at the transmitting station A, the line is energized, as described in detail later, thereby energizing magnet SSM. The armature SSMA is thereby

attracted so that arm 103 is rotated clockwise against the force of spring 103s, as viewed in Fig. 17, and the lug 104 is rotated into position to intercept the stop pin 104B and the clutch is thereby arrested in the normal stop position. Upon transmission of the normal start or "spacing" line condition, magnet SSM is again deenergized and the arm 103 is rotated counterclockwise, as viewed in Fig. 17, to release pin 104B. As is more clearly illustrated in the diagrammatic illustration of Fig. 4, this release will permit the start-stop clutch 102 to rotate until either the preliminary stop pin 104A is engaged at the end of nearly a full revolution or under ordinary operation until pin 104B is engaged, which occurs at the end of one complete revolution during this normal operation when a stop or "marking" line condition is transmitted over the line which stop signal energizes magnet SSM to attract armature SSMA to rotate arm 103 to the position as diagrammatically illustrated in Fig. 4, also described in detail later.

Upon release of the stop pin 104B, during transmission of the start or "spacing" line condition, as described above, the controller ring 124 is rotated in the direction of rotation of the clutch 102 by the torque spring 126. Simultaneously, the friction due to washer 128 and cup-shaped spring washer 129 rotates the cage 123 in the direction of rotation of the clutch but the quick action of the spring 126 engages the rollers 122 between the spider and the driver cup by moving the rollers towards the shallow end of the eccentric openings 124a (Fig. 26). Upon engagement of rollers 122, spider 125 and driver cup 120, the start-stop shaft 99 is rotated. The clutch pick up is most rapid and the clutch engages almost instantaneously with the reception of the start signal. Rotation of the start-stop shaft produces rotation of the cams TX, TL, TI to T6, inclusive, and TP, to thereby actuate the associated push pins sequentially and thereby control the associated contacts to condition the associated circuits, as will be explained in detail later. Upon receipt of the stop signal, at the end of one cycle of operation, the start-stop magnet is energized whereby the armature SSMA is attracted to rotate arm 103 clockwise and the lug 104 is moved into position to engage the stop pin 104B, at the normal stop position, thereby limiting the start-stop clutch 102 to a single revolution only. Upon engagement of the lug 104 with pin 104B, the rotation of the controller ring is arrested but the momentum of the other parts of the clutch places a stress on the torque spring 126 and disengages the rollers 122 from the spider 125 and the driving cup 120, so that the rollers are moved to the disengaged position, as illustrated in Fig. 26, and the start-stop clutch is stopped.

Referring to the embodiment of the start-stop single revolution clutch mechanism as illustrated in Figs. 27 to 35, inclusive, this mechanism can be mounted on the vertical side plate 101 of the distributor unit (Fig. 17) and utilized to replace the start-stop single revolution clutch mechanism, above described. The construction of the clutch of these figures is generally similar to that of Figs. 25 and 26, with the exceptions as noted above. Referring to Figs. 30 to 35, inclusive, there is illustrated therein a special stop pawl mechanism which is employed to provide quick and uniform release of the single stop pin 104SP attached to the controller ring 124 of the clutch of Figs. 27-29, inclusive and to limit the start-stop shaft to a single revolution following the de-

energization of the start-stop magnet, so that in the event that the line circuit is open, the start-stop magnet is prevented from running idly and thereby assuming an out of synchronism position.

5 Upon reclosing of the line circuit, the start-stop shaft remains stopped until the next start signal, hence false printing on opening and closing of the line, as would occur with a simple stop pawl, is prevented. As seen in Fig. 30, the stop 10 pawl 104 is carried by an arm 103a pivoted at 103p so that the pawl will normally engage the single stop pin 104SP. A cross latch member 133 is mounted at one end thereof, on the start-stop armature SSMA, and at the other end is guided vertically by a bracket 133b having a guide slot formed therein. A stop 133a is formed in the cross latch which stop cooperates with a lug 103b formed on the arm 103a. A follower portion 133b is also formed on the cross latch which follower portion cooperates with the rebound cam 131c, as is seen in Fig. 30. A spring 133s is mounted between the arm 103a and the cross latch 133 and a spring 135 is connected to a pin 135a at one end and attached by means of an opening 136 to the cross latch 133, at the other end thereof, the spring 135 serving to pull the cross latch to the left, as viewed in Fig. 30, and to pull the armature SSMA away from magnet SSM upon deenergization thereof.

20 The rebound lever 132 cooperates with the rebound cam 131c and rides on the outer periphery of the cam to thereby oscillate counterclockwise about the pivot 132p against the force of a spring 137 connected at one end to a support pin 137a and attached to the lever 132 by means of the opening 138 therein.

25 The operation of the novel single revolution mechanism is as follows: Assuming that the line is energized and that magnet SSM is energized, the elements of the single revolution mechanism are then in position, as illustrated in Fig. 30. The start-stop shaft is arrested and the clutch is disengaged due to the engagement of the lug 104 and stop pin 104SP. Upon receipt of a start signal represented by a "spacing" condition of the line, magnet SSM is deenergized whereupon spring 135 pulls the cross latch 133 to the left (Fig. 32) and by engagement of the step 133a and the lug 103b, the stop pawl 104 is moved out of the path of the stop pin 104SP and the clutch and start-stop shaft begin rotating in a counterclockwise direction. As the start-stop shaft rotates on its first complete revolution, the rebound cam is thereby rotated and after approximately a half revolution is completed, as is illustrated in Fig. 34, the rise on the cam 131c, cooperating with the follower 133b, moves the cross latch 133 downwardly, whereby the step 133a is disengaged from the lug 103b and the spring 133s thereupon rotates the arm 103a counterclockwise until it abuts the stop pin 138 so that the arm 103a moves the pawl 104 to the stop position thereby permitting only one complete revolution of the clutch. When the stop pulse or a marking condition of the line is received, the magnet SSM is energized and attracts armature SSMA to move the cross latch 133 to the right, to the position as illustrated in Fig. 30, whereupon the step 133a engages the lug 103b so that release of the armature can again release the clutch. It is seen, therefore, that the novel start-stop single revolution clutch mechanism of Figs. 27 to 35, inclusive, provided with a single stop pin, can be utilized to replace the double stop pin clutch mechanism of Figs. 25 and 26

utilized in conjunction with control mechanism as illustrated in Figs. 15 and 17.

Mechanism for locally producing shift or carriage-return and simultaneously producing a shift or carriage-return signal for remote control of these functions, will now be described. The mechanism is of the type as disclosed in the copending application of Harry J. Nichols and Henry Tholstrup, Serial No. 353,113 filed August 17, 1940. Referring to Fig. 36, a standard power cam 139 for locally producing shift, which shift cam is, as is well known, normally operative upon the downward stroke and also operative on the upward stroke, is operatively connected for control thereby in the well known manner, to an extension 140a of an auxiliary key lever 140 in this instance, instead of being operatively connected to the standard Figs. key lever 52F. Key levers 140 and 52F are mounted for rotation about the cylindrical rod element 141, in a manner well known in the art, the key lever 52F by means of its extension 55 controlling a single half revolution cam 62, as in Fig. 2.

The Figs. key lever 52F is remotely controlled upon reception of a signal by a key solenoid KS and its connecting spring CS, as diagrammatically illustrated in Fig. 2. The power shift cam when operated by remote control or when digitally operated controls in a normal manner the shifting of the typewriter basket locally, to "Figs." case by operation of the key lever 140 and consequent downward stroke of the extension 140a while upon the upward stroke of lever 140, produced by means of interconnecting mechanism as described later upon depression of the letters key 51L, the basket is locally shifted to the "Letters" case. The "Letters" key lever 52L may be remotely controlled by means of a solenoid KS and connecting spring CS, in the same manner as the key lever 52F and the "Letters" key lever 52L, by means of its extension 55, controls a standard, single half revolution power cam 62 having a slider actuating roller 79 mounted on an extension of the support arm thereof, as in Fig. 2. A rocker lever 142 is pivotally mounted on the frame 143 by means of a pivot screw 144. An L-shaped lug 145, integral with the left end of the lever 142, engages in an opening 140b formed in the auxiliary key lever 140. The "Figs." key lever 52F in its unoperated position, abuts the top of the rocker lever 142, and upon depression of the key 51F, will rotate the rocker lever counterclockwise. Likewise, the "Letters" key lever 52L, in its unoperated position, abuts the top of the rocker lever 142, and upon depression of this key lever it produces clockwise rotation of the rocker lever. A spring arm 146, attached to the frame 143, is provided with a circular protruding element 147 which engages in either an upper indentation 148 or a lower indentation 149 formed in the right hand end of the rocker lever 142. When the rocker lever is rotated clockwise upon depression of the "Letters" key 51L, the protruding element 147 engages the top indentation 148 of lever 142, as shown in Fig. 36, to thereby hold the rocker lever in the extreme clockwise position. Likewise, when the lever 142 is rotated counterclockwise by depression of the "Figs." key 51F, the element 147 engages the lower indentation 149 to hold the lever 142 in its extreme counterclockwise position.

The operation is as follows: The "Figs." key 51F is first depressed and allowed to return to its normal position. Depression of the "Figs."

key not only releases its associated cam 62, in the well known manner, to permit roller 79 to operate the associated slider, as in Fig. 2, to set up the permutation code signal characteristic of "Figs." shift but also rotates the rocking lever 142 counterclockwise, and this lever is held in the extreme counterclockwise position by means of spring arm 146, element 147 and indentation 149. Counterclockwise rotation of the rocker lever depresses the key lever 140 by means of the L-shaped lug 145 integral with the lever 142. Upon depression of lever 140, this lever remains down, releasing cam 139 for a half revolution only, whereby the type basket is locally shifted to the "Figs." case and will remain in that condition until the "Letters" key is depressed.

Upon depression and release of the "Letters" key 51L, not only is its associated cam 62 released to rotate a half revolution, so that roller 79 will operate its associated slider in a manner now well understood, to set up the permutation code signal representative of "Letters" shift, but also the rocker lever 142 is rotated clockwise to thereby raise lever 140 to release cam 139 for another half revolution, whereby the type basket is locally shifted to "Letters" case.

Successive depressions of the "Figs." key or of the "Letters" key will permit repeat signals to be transmitted to the line but will not at all affect the rocker lever 142 so that the typewriter basket will locally remain in either "Figs." case or "Letters" case depending upon whether the "Figs." key or "Letters" key is being successively depressed.

There is also disclosed in Fig. 36, the carriage-return signaling and operating arrangement, as disclosed in the above mentioned application. It is to be noted that in the standard "Electromatic" typewriter, the carriage-return power cam is of the single lobe type, in contrast to the double lobe type of cam as illustrated in Fig. 2. Upon actuation of the carriage-return key, the single lobe cam is locked in operative position until the typewriter carriage completely returns to the left hand margin. Due to the variable operating time of the carriage-return cam, means must be provided to produce a signal, corresponding to carriage-return, in order that the signal will occupy the same time interval as all other signals.

Referring to Fig. 36, a carriage-return lever 52CR is mounted for rotation about the rod 141 as a pivot, in a well known manner. An auxiliary lever 150 is likewise mounted for rotation about rod 141. A generally U-shaped connecting link 151 is pivotally mounted in a bracket 152 fastened to a part of the frame by any well known means. One end of the link 151 engages in an opening formed in the key lever 52CR while the opposite end of the link 151 engages in an opening formed in the lever 150. The carriage-return lever 52CR controls the usual single lobe cam (not shown) producing carriage-return locally. The lever 150, controls an ordinary standard two-lobe power cam (not shown) in the same manner as lever 52L, for example.

The operation is as follows: Upon depression of the carriage-return key 51CR, a single lobe power cam is released and the carriage at the local machine is returned to its left hand margin.

Simultaneously, upon depression of the key 51CR, the lever 52CR is depressed and link 151 operates thereby depresses lever 150 thereby releasing the ordinary two-lobe power cam such as 62 associated therewith, to set up the car-

riage-return signal permutation, so that consequently the machine at the remote station is controlled by the received signal to operate the carriage-return lever at said remote station, and thereby produce a return of the carriage at the remote machine, to its left hand margin. By utilizing the combination of lever 52CR and lever 150 with the respective cams as controlled by these levers, the function of carriage-return is locally produced, in the usual manner, and a carriage-return signal of equal duration to all other character or function representing signals is transmitted to the remote station.

Receiving mechanism

The receiving mechanism and related circuits is illustrated diagrammatically in Fig. 7 but it is to be particularly noted that such circuits and mechanisms are provided at both the sending and the receiving machines and it is also to be particularly noted that a part of the transmitting mechanism, per se, is also utilized in the receiving function. It is also to be particularly noted, as described in detail above, that elements of the transmitting mechanism and of the receiving mechanism are mounted upon a single start-stop shaft 99 as illustrated in detail in Figs. 15 and 16 and that the sending mechanism at one station is used solely for the purpose of transmitting while the corresponding sending mechanism, at the station designated for receiving, is utilized during the receiving function, as will be described in more detail later. The receiving mechanism, separate from any sending mechanism utilized during the receiving function, comprises a plurality of receive cams mounted on the same start-stop shaft 99 as the transmitting cams, as illustrated in Figs. 15 and 18, these receiving cams being positioned so as to wipe the oiler wicks OW (Fig. 18) and controlling tumblers, as illustrated in Figs. 18 and 22, the tumblers being diagrammatically illustrated only, in Fig. 7, to thereby position the respective cascade switch tongues of the electrical translator, as illustrated diagrammatically in Fig. 7. The tumblers are controlled by a shuttle magnet respectively energized or de-energized by the nature or electrical quality of the sequential code components representing a character and by a shuttle whose position is regulated by the shuttle magnet, as explained later, whereby the tumblers are set in accordance with the electrical quality of the code components of a line signal to thereby position the cascade switch tongues of the electrical translator so that one key solenoid only is selected and subsequently operated to type the character corresponding to a character key depressed at the sending station.

Another embodiment of novel selector or cascade switch tongue controlling mechanism is illustrated in Figs. 23 and 24, which mechanism, under the control of a shuttle magnet, may also be utilized to position the cascade switch tongues in accordance with the components of a received line signal.

Referring to Figs. 15, 17 and 22, the construction arrangement and operation of the signal storage mechanism, will now be described in detail. This signal storage mechanism is of the mechanical storage type which mechanism in turn controls the cascade switch tongues of the electrical translator, as stated above. In the present novel selector mechanism, the restore function, as utilized in the prior art, has been

eliminated, and the only elements of the mechanism operated by each received permutation of signal components, are those which are controlled by components different than the corresponding component of the preceding permutation. The setting is therefore by difference, generally as set out in the description of the operation of the permutation unit. The speed of operation is thereby increased without any decrease in dependability.

Referring to Figs. 15 and 17, the horizontal start-stop shaft 99 which, as previously described, operatively carries transmission cams also carries the receive cams. A receive cam sleeve 154 is mounted on the start-stop shaft 99 and is fastened thereto by any well known means such as a set screw 154a, so that the sleeve rotates with the shaft. A key way 109a is formed in the outer periphery of the sleeve in which key way is positioned a cylindrical key 110a coaxial with the inner periphery of the receive cams to lock the cams and cam sleeve together for simultaneous rotation by means of the start-stop shaft. The receive cams R1, R2, R3, R4, R5 and R6 are axially sequentially mounted on the sleeve 154, from left to right, as schematically illustrated in Fig. 20. Each cam is separated from the other cams by a series of spacer rings 101a and the receive cams are clamped against the flange 154f and against each other by means of the nut 99b mounted on the threaded end 99a of start-stop shaft 99. By loosening the set screw holding the cam sleeve to the start-stop shaft and by loosening the nut 99b, the receive cam sleeve can be slightly rotated with respect to the transmitting cams so that the stop or rest position of the receive cam sleeve can be oriented to produce the positioning of the tumblers at substantially the mid-portion of signal components received.

A series of six storage tumblers ST1, ST2, ST3, ST4, ST5 and ST6, as illustrated diagrammatically in Fig. 22, are controlled by the respective cams R1—R6, inclusive, and associated mechanism as will be explained presently. Referring to Fig. 18, the tumblers are shown as vertically mounted in proper alignment by means of a guide plate 155 securely held to the side frame plates 101 by means of screws 156 (Fig. 17) and a tumbler guide comb 157 mounted on support 158 held in place by screws 159. A supporting member 160 is mounted on the guide comb by means of screws 161. Each storage tumbler is, therefore, mounted for free movement upwardly and downwardly to thereby close and open respectively, the cascade switch tongues of the respective cooperating switches RX1 to RX6, inclusive, which switches comprise elements of the electrical translator as diagrammatically illustrated in Fig. 7. Each tumbler is provided with a pawl 162 (Fig. 22) having a horizontally projecting portion 162a and mounted on a pivot 163 carried by the tumbler so that the pawl may be oscillated by the cooperation of the projecting portion 162a and the respective cooperating receive cam. A latch spring 164 and an auxiliary latch spring 165, mounted on a support 166 cooperate with a horizontally formed shoulder 167 on each tumbler and with a pawl 162, respectively. The latch spring 164 retains the associated storage tumbler in its uppermost position when moved to that position by the associated receive cam, as described presently, and also serves to absorb the shock of the tumbler as it is urged downwardly by the reaction of the cascade spring tongues comprising the cen-

ter element of the translator switches. The auxiliary latch spring 165 exerts a lateral resilient pressure on the pawl to maintain it in position to be operated by the associated receive cam.

A shuttle member 168 (Fig. 15) having a series of six slots 169 formed in one edge thereof is frictionlessly sustained by and between two flat springs 170 riveted to a supporting bracket 171. The supporting bracket is provided with two elongated slots 171s into which enters screws 172 to hold the shuttle assembly in position above the top plate 155. The shuttle can be transversely adjusted due to the elongation of the slots 171s. An adjustable stop 173 comprising an eccentric washer held by a clamping screw 174 determines the position of the shuttle when in its unoperated position which position can be varied by adjustment of the stop. The shuttle 168 is under the control of a shuttle magnet SM (see also Fig. 7) by means on an arm 174 (Fig. 17) pivoted at 175 on a bracket 176 fastened to an end plate 101 by screws 177 (Fig. 15). The arm 174 is integrally connected to the armature SMA of the shuttle magnet so that the arm is oscillated about pivot 175 upon energization of SM and is returned to the unoperated position by means of the spring bias of springs 170 which hold the shuttle ensemble against the stop 173, as illustrated in Fig. 15. An end 174a of arm 174 passes through an opening 178 (Fig. 15) so that oscillation of the shuttle magnet produces lateral movement of the shuttle 168 in accordance with the line conditions controlling the magnet and comprising the separate components of a complete character or function representing signal. As seen in Fig. 15, a series of six slots 179 are formed in the top plate 155 in alignment with the six tumblers, respectively, while the slots 169 formed in the shuttle 168 are out of alignment with slots 179, the teeth 168t of the shuttle being partly aligned with and obstructing slots 179, in the unoperated position of the shuttle.

As seen in Fig. 18, each of the tumblers is provided with an operating cylindrical shaped end 162a which coacts with the movable cascade spring tongues of the respective switches of the electrical translator. The respective disposition and number of the switch tongues with respect to the operating ends 162b is illustrated in Fig. 17.

The operation of the storage mechanism is as follows: Referring to Figs. 21 and 22, a series of line conditions as in Fig. 21, are considered as applied to the shuttle magnet SM (Figs. 7 and 17) thereby actuating the shuttle 168 upon reception of a marking signal to align the slots 169 (Figs. 15 and 22) of the shuttle 168 with the slots 179 of the top plate 155 or upon reception of a spacing signal to permit the shuttle 168, when previously operated, to return to its unoperated position wherein a tooth 168t of the shuttle is aligned with each of the slots 179 in the top plate 155. The first signal element is invariably a spacing signal whereby the start-stop magnet SSM (Fig. 17) releases the start-stop clutch 102 and the start-stop shaft 99 at the receive station is set into rotation in synchronism with the start-stop shaft 99 at the send station. Rotation of the start-stop shaft rotates the send cams at the receive station which send cams also take part in the receiving function, as will be explained presently. Likewise rotation of start-stop shaft 99 rotates the receive cams R1 to R6, inclusive. Rotation of the receive cams brings the receive cams, sequentially into contact with the extensions 162a (Fig. 22) of the pawls 162, in the

sequence as determined by the diagrammatically illustrated relative positioning of the receive cams in Fig. 20. At the middle of the first selecting signal component, which is a marking impulse component (see Fig. 21), the cam R1 engages the extension 162a of pawl 162, mounted for oscillation by pivot 163, on switch tumbler ST1. Since the signal component is, as stated, a marking impulse, the magnet SM is energized and the shuttle 168 is moved to the right, as viewed in Fig. 17, so that a slot 169 (Figs. 15 and 22) is moved into alignment with a slot 179 in a top plate 155. The rotation of receive cam R1, therefore, merely oscillates the pawl 162 counterclockwise about its pivot 163 against the force of its auxiliary spring 165. The switch tumbler ST1, therefore, remains in its lowered position and its operating end 162b merely abuts the coacting movable cascade spring tongue 180 so that tongue 180 remains in engagement with contact 180a and out of engagement with 180b.

Upon reception of the second selecting signal component, which, as noted from Fig. 21, is another marking component, the extension 162a of pawl 162 mounted on switch tumbler ST2 is engaged by the cam R2 which thereupon rotates the pawl 162 counterclockwise, and as described in connection with ST1, the end of tumbler ST2 merely abuts the cascade switch tongue 181 (Figs. 7 and 17) so that tongue 181 under this condition of operation will remain in engagement with contact 181a and out of contact with 181b, as shown in Fig. 7. Also, as is seen from Figs. 7 and 17, the switch tumbler ST2 controls both of the gang operated movable cascade switch tongues 181 and 182, simultaneously, so that upon reception of the second marking signal component, under the conditions assumed, switch tongue 182 remains in engagement with contact 182a and out of engagement with contact 182b.

Upon reception of the third selecting signal component, which, as is seen from Fig. 21, is a spacing condition, the receive cam R3 at the midpoint of this signal component has meanwhile been rotated into contact with the extension 162a of pawl 162, pivotally mounted on switch tumbler ST3. Upon reception of the spacing signal, the shuttle magnet SM (Fig. 17) is deenergized and the shuttle aligns a tooth 168t with a slot 179 (Fig. 15) of the top plate 155. As the cam R3 continues its clockwise rotation (Fig. 22) the upper end of pawl 162 is held in engagement with a tooth 168t of the shuttle and the storage tumbler ST3 is therefore lifted vertically by the engagement of the cam R3 with the extension on lug 162, until the end of latch spring 164, associated with tumbler ST3, is located under the shoulder 167 of the tumbler, to hold it in its elevated position, upon release of the pawl 162 by its operating cam. Elevation of the tumbler ST3, raises its operating end 162a to thereby move the switch blade 183 out of engagement with contact 183a and into engagement with 183b. Likewise, the gang operated cascade switch tongues 184, 185 and 186 (Figs. 7 and 17) are moved out of engagement with one of its pair of cooperating contacts and into engagement with the other.

The operation of switch tumbler ST4 is similar to that of ST3, under the line conditions as assumed in Fig. 21, and the gang switch tongues 187, 188, 189 and 190 (Figs. 7 and 17) are moved, respectively, out of engagement with the corre-

sponding *a* contacts and into engagement with the corresponding *b* contacts.

Upon reception of the fifth selecting signal component, which, as is seen from Fig. 21, is a marking component, the pawl 162 associated with switch tumbler ST5 is rotated counterclockwise. It is assumed, however, that the switch tumbler ST5 was raised by the previous fifth selecting signal component of the prior signal. The counterclockwise rotation of pawl 162 against the force of auxiliary latch spring 165 removes the latch spring 164 from beneath the shoulder 167 of switch tumbler ST5 and the tumbler is thereupon moved to its lowered position, under the spring action of cascade switch tongue 191 so that tongue 191 is moved out of engagement with contact 191b and into engagement with contact 191a. Likewise, the associated gang operated switch tongue 192 (Figs. 7 and 17) is moved out of engagement with contact 192b and into engagement with 192a.

Upon reception of the sixth selecting signal component, which, as is seen from Fig. 21, is a spacing component, the shuttle magnet is actuated to align a tooth 168t of the shuttle with a slot 179 (Fig. 15) in the top plate, in the same manner as described in connection with switch tumblers ST3 and ST4. It is assumed, however, that the switch tumbler ST6 was elevated by the sixth selecting signal character component of a previous signal. The tumbler ST6, therefore, is being held in its elevated position by the engagement of the end of its associated latch spring 164 with the shoulder 167 on tumbler ST6. Upon rotation of receive cam R6 into position where it would ordinarily engage with the extension 162a of pawl 162, the top end of the pawl being in engagement with a tooth on the shuttle, the tumbler would ordinarily be elevated. Since, however, the tumbler was elevated by the previous character signal and is held in its elevated position by the spring 164, the receive cam R6 upon engagement with the extension 162a of pawl 162, mounted on switch tumbler ST6, merely elevates the tumbler slightly, the engagement of tooth 168t with the top end of pawl 162 preventing counterclockwise rotation thereof and the switch tongue 193 remains in engagement with contact 193b and out of engagement with 193a. It is seen, therefore, from the above detailed description, that the operation of the tumblers is predicated on the differential principle and only those tumblers are actuated which require a change from the previous signal setting. The speed of operation of the selector mechanism is therefore greatly increased over that of selector devices of the prior art.

Referring to Figs. 23 and 24, there is illustrated therein another embodiment of a novel selecting mechanism including a slider 194 which embodiment can be controlled by means such as a shuttle magnet SM (Fig. 17) it being assumed, in the instant embodiment, that the slider 194 is actuated by a member 195, connected in any desired manner to the armature SMA (Fig. 17) of shuttle magnet SM. Further, the receive cam elements R1a-R6a, inclusive, can be considered as mounted upon the start-stop shaft 99, as are the receive cams R1-R6, inclusive, of the device of Figs. 15 and 20.

The receive cam elements comprise a series of double cam members R1a-R6a, inclusive, mounted on a cam sleeve 154, held in operative relationship with start-stop shaft 99 by means such as set screws 154s, so that the sleeve rotates

with the shaft. A key way 109a (Fig. 24) is formed in the outer periphery of the sleeve, in which is positioned a cylindrical key 110a coacting with the inner periphery of the receive cams to thereby lock the cams and cam sleeves together for simultaneous rotation by means of the start-stop shaft 99. The receive cams R1a-R6a, inclusive, are sequentially mounted on the sleeve 154, from left to right and are so relatively positioned, circumferentially of the sleeve, that the tumblers controlled thereby will be sequentially operated in accordance with the sequence of code signal components received by the shuttle magnet SM operating the slider 194 through the connecting means 195. Each cam is separated from the other cams by a series of spacer rings 107a and the receive cams are clamped together by means of the internally threaded nut members 196 mounted on portions 196a of the sleeve. A pair of collars 197, secured to the start-stop shaft 99 by means of set screws 197a, prevent axial movement of the sleeve.

Each of the double cams comprises a pair of flange members 198a and 198b at the opposite axial ends of the cam member and a separating wall member 199 dividing the cam member into two separate cam peripheries 198c and 198d. A notch 199a is formed in the wall member, opposite a cam drop 200 formed on each of the two cam peripheries of each double cam member and on opposite sides of the notch. One of the cam peripheries of each double cam is provided with a hump portion 201 (Fig. 24) for producing elevation of the cooperating storage tumbler at a predetermined point in the rotation of the double cam.

The tumbler members ST1a to ST6a, inclusive, comprise a slot enclosing portion 202 (Fig. 24), a rounded end portion 203, an elongated neck portion 204 and an operating end 205. The shuttle 194 is mounted in the support arms 206 for longitudinal reciprocation therein by means of the operating member 195 connected to the shuttle magnet (not shown). Shuttle 194 passes through the slots in the slot enclosing portions 202, each tumbler being generally aligned with a notch 199a in the shuttle. The end portion 203 of each tumbler normally rides on one of the peripheries of one of the double cams so that the top portion of the walls of the respective slots are out of engagement with the shuttle and the shuttle can reciprocate freely and easily. Each tumbler is guided, for vertical movement, by slots in a guide member 207. A washer member 208 abuts the top of the slotted portion 202 (Fig. 24) and a coil spring 209 compressed between the guide member 207 and the washer, lightly biases the tumblers against the cams.

The operation is as follows: As the start-stop shaft 99 rotates in synchronism with the code components of the signal actuating the shuttle magnet, the shuttle 194 is positioned in accordance with the electrical quality of the particular signal code element. Assuming, for example, that the electrical quality of a particular signal code element is such as to condition the shuttle magnet SM (Fig. 17) to move the shuttle to the right, as viewed in Fig. 23. It is to be noted that the shuttle is moved to the right just prior to rotation of a cam drop 200 into alignment beneath the particular tumbler to be actuated. Upon such rotation, the tumbler is no longer supported by a cam periphery, the spring 209 forces the tumbler positively downward and the tumbler, in its downward move-

ment, slides down the left hand inclined boundary 194L of a slot 194a. Since a notch 199a, is formed in the cam separator wall 199 opposite each cam drop, the lower end of the tumbler is moved from engagement with the periphery of a cam surface 198c into engagement with a cam surface 198d. It is to be particularly noted, that unless the corresponding signal component in the next character representing signal has a different electrical quality, the tumbler remains in this set position, so that the tumbler setting is again predicated upon the differential principle.

Assuming, for example, that a tumbler is in the position as illustrated by tumbler ST4a in Fig. 23 and that a particular electrical quality of a signal component received is such that shuttle 194 is moved to the right. Upon alignment of the cam drop 200 with the bottom of tumbler ST4a, the tumbler is merely momentarily depressed but remains in engagement with cam surface 198d. If, however, the signal component were such that the shuttle 194 remained, as illustrated in Fig. 23, the tumbler would be moved from engagement with cam surface 198d into engagement with cam surface 198c.

One of the cam surfaces, either 198c or 198d, is provided with an operating hump 201 (Fig. 24) so that, at a predetermined time in the rotation of a cam the cooperating tumbler may be elevated. The tumblers may be sequentially elevated, as in the device of Fig. 20, or the tumblers may first, be all set into engagement with either the corresponding left hand cam periphery 198c or right hand periphery 198d, and then simultaneously elevated, just prior to the print signal being transmitted to the translator. The latter structure is illustrated in Fig. 24.

If desired, however, the first three cams can be set either sequentially or simultaneously to choose a group relay of the electrical translator, as described later, and the remaining three cams may be set later, either sequentially or simultaneously, just prior to the print signal. The desired sequence of operation is determined by the position of the operating hump 201 with respect to the cam drop 200 and the particular time of operation can be slightly adjusted by orienting the cams circumferentially or the particular time of operation can be predetermined by the relative disposition of the cam drops of the separate cams with respect to each other and with respect to the operating humps.

Novel means are therefore provided for positioning the cascade switch tongues of the electrical translator by simple and effective means and in a positive manner, and the sequence of operation of the switch tongues can be predetermined, as desired.

Send receive relay

The send receive relay SRR1 at the sending machine (Fig. 3) comprises a relay proper, of the well known type commonly referred to as a telephone relay. On the core 210 is wound a coil of approximately 3500 ohms resistance comprising the winding W which is shunted by a storing condenser C1. At the heel of the core is assembled a concentric sleeve or "slug" of copper 211. This assembly comprises a well known, quick-acting, slow-release relay wherein the relay is quickly energized by a pulse and maintains its armature and associated contacts in attracted position for a period determined by the electrical constants of the respective arts.

The relay is so designed that upon energization of the relay by an electrical pulse, even though the energizing pulse is then removed, the energization of the complete relay including the coil and shunting condenser maintains the relay armature and associated contacts in the attracted position until the send-receive shaft 99 has rotated from its normal start position (start-stop relay and line energized) to the position wherein the transmission cam T6 (Fig. 4) mounted on the start-stop shaft 99, closes the contacts comprising switch TX6 so that, during this rotation, all signal components are transmitted through the send-receive relay contacts to the line. As will be explained in detail later, a stop pulse is thereupon transmitted through the send-receive relay to the line so that the send-receive relay is maintained continuously energized during operation of the transmitting device.

Referring to Fig. 5, the operation of the send-receive relay SRR1 is as follows: It is first assumed that the line between stations A and B (Fig. 1) was previously deenergized. Since the line is deenergized, the line relay LR1 (Fig. 6) has its armature in the spacing position or in other words, in engagement with contact S so that the circuit through the start-stop magnet SSM1 (Figs. 5 and 6) is open at contact M and relay SSM1 is deenergized to release its armature and stop arm 103, so that the start-stop clutch 102 was arrested with its preliminary stop 104A in engagement with the stop arm 103 diagrammatically illustrated only, in Figs. 3, 4, 5, 6 and 7. In this position, the contacts 211 and 212 of switch TXC are in engagement and contacts 212 and 213 are out of engagement, so that the circuit from battery B1, contacts 212 and 213, the coil of relay CR1 to ground, is open at contacts 212 and 213.

In order to energize the line, which is the normal condition for operation in the present system, the key SRK1 (Figs. 3 and 5) is depressed, thereby closing a circuit from battery B1, contacts 88, 88a, contact 87UXa, contact 87UX, to coil W of relay SRR1, the single blade of key SRK1, contact 214 to ground thereby charging the condenser C1 and energizing the coil W of the relay so that the armature 215 is attracted to close the cooperating contacts of the relay and to hold the relay energized for a predetermined period, as described above. When the start-stop shaft 99 is in its preliminary stop position, the energization of relay SRR1, upon depression and release of the key SRK1 thereby closes the following holding circuit: From battery B1 (Fig. 3), contacts 88, 88a, contacts 87UXa, 87UX, coil W of relay SRR1, switch tongue of key SRK1, contact 216, relay contacts 217 and 218 of SRR1 (now energized), coil of line relay LR1, to the line, to coil of line relay LR2, contacts 219 and 220 of relay SRR2 to ground, thereby maintaining the relay SRR1 energized. Energization of the line and of the coil of line relay LR1 causes the armature of LR1 to move to marking position and thus into engagement with contact M so that a circuit is closed from battery B1, to contacts 212, 211 of switch TXC, to start-stop magnet SSM1, to contact M, to the armature of LR1, to ground, thereby energizing SSM1 to cause it to attract its armature 103 to release the armature from engagement with stop pin 104A (Fig. 5) and to allow the clutch 102 to rotate until stop pin 104B is engaged by stop

arm 103 (Fig. 3) and the clutch is stopped in the normal stop position.

Control relay

In the preliminary stop position (Fig. 5) and in the normal stop position (Fig. 3), contacts 212 and 211 of switch TXC are in engagement and the contacts 212 and 213 are out of engagement, so that control relay CR1 is deenergized. Control relay CR1 controls the contacts 88 and 88a in a line leading from the battery B1 to contacts 87UXa and 87UX controlled by the universal bail. As described above, therefore, when the start-stop clutch 102 is in the normal stop position (line energized), the send-receive relay SRR1 is energized through the contacts 88, 88a controlled by magnet CR1 and through contacts 87UXa and 87UX controlled by the universal bail. Upon depression of any key to type a character or to produce a function, the universal bail contacts are opened, as previously described, and the energy source B1 is disconnected from the send-receive relay SRR1. Likewise, upon depression of any key, the clutch 102 is released, as described in more detail presently, and the start-stop shaft 99 begins to rotate. This rotation produces rotation of the control cam TC, so that contacts 212 and 211 are disengaged thereby isolating the start-stop magnet SSM1 from battery B1 and also from control by the line signals and upon such rotation of cam TC contacts 212 and 213 engage, thereby energizing the coil of magnet CR1 by a circuit extending from battery B1, contacts 212 and 213, coil of CR1 to ground. Energization of magnet CR1 opens the contacts 88 and 88a so that, even though the universal bail contacts are closed, when the key, originally depressed, is consequently released, nevertheless the circuit from battery B1 to the universal bail contacts is open at contacts 88 and 88a so that the universal bail contacts are no longer supplied with energy. This circuit is held open until after the last signal code element has been transmitted through the switch TX5 (Fig. 4) whereupon contacts 213 and 212 are opened and contacts 211 and 212 are closed, the opening of contacts 213 and 212 deenergizing the coil of CR1 and permitting contacts 88 and 88a to close so that the stop or "marking" line signal element is transmitted from battery B1 to relay SRR1 and to the line via contacts 88, 88a, 87UXa and 87UX in series. It is to be particularly noted, therefore, that novel means, extraneous from the transmitting mechanism per se, are provided, whereby the circuit to the line is disconnected, except through the particular permutation switches closed for any particular character or function, and that the same circuit to the line is closed in time to transmit the stop or "marking" line signal element.

Speed lock system

Referring to Figs. 6 and 7, there is disclosed therein a speed lock circuit which controls a keyboard lock for preventing depression of more than one key of a keyboard, during a particular signal period. The circuit and means comprising the speed lock system which also comprises a part of the "break-in" system are of the type as disclosed in the above mentioned copending application.

Upon depression of any chosen character key of the typewriter keyboard, the universal bail contacts 87UXa and 87UX are opened, thus breaking the line circuit, deenergizing the re-

spective line relays and causing transfer of the line relay armature from the marking to the spacing contact, so that start-stop magnet SSM1, for example, is released, to begin rotation of the start-stop shaft 99 carrying the speed lock cam TL. As cam TL rotates, the contact 224, which in the normal stop position of the clutch (Fig. 7) is mid-way between contacts 223 and 225, is moved into engagement with contact 223. Closure of contacts 224 and 223 closes a circuit through the coil of the speed lock magnet SLM1 as follows: From battery B1, coil of the speed lock SLM1, contacts 224 and 223, contacts 226 and 227 of relay SRR1 (now closed) to ground. The latch magnet will remain established by cam TL until shortly before the end of the cycle thereby, by means of the mechanism as described in said copending application, preventing depression of any other key or even repeated depression of the same key until the distributor has transmitted all the elements of the signal.

Break in

The speed lock arrangement above described is utilized as one of the elements of the "break in" arrangement, all as described in detail in the above mentioned copending application. Assuming that during transmission of a message, the operator at receive station B wishes to interrupt and to reverse the direction of transmission. The operator at station B thereupon (Fig. 3) depresses the key SRK2 and holds this key down until the send-receive relay SRR1 at station A has time to become completely deenergized. When key SRK2 at station B is depressed, the following circuit is closed: From battery B2, contacts 88 and 88a of control relay CR2 at station B, contacts 87UXa, 87UX of the universal bail, condenser C2 and the winding W of the send receive relay SRR2, send-receive key SRK2, contact 214 to ground. Energization of the send-receive relay SRR2 causes transfer of its associated contacts so that upon opening of contacts 219, 220 of relay SRR2, the line circuit from station A to ground at station B is interrupted long enough for SRR1 to become completely deenergized, or for a full signal period. Such interruption, therefore, deenergizes SRR1 at station A, transferring its contacts to the receive or normal position. When SRK2 is released, relay SRR2 is now in a send condition and relay SRR1, as stated above, is in the receive condition instead of its previously send condition. It is to be noted that the start-stop clutches 102 at both stations have been arrested in their normal stop positions. The speed lock, as described above, locks the keyboard at station A, in the manner as set out in detail in the above mentioned copending application, to indicate to the operator at station A, that the line circuit has been interrupted from the receive station and that the operator at station B wishes to take over.

Referring to Figs. 3 and 6, when the key SRK2 at station B was depressed to interrupt the signaling and to open the line, the line relays LR1 and LR2 were deenergized and their armatures were transferred from the marking to the spacing contact. Upon such transfer, the start-stop magnet circuits at both stations were opened at the marking contacts and the start-stop magnets at both stations were deenergized thereby releasing the stop arms 103 which interrupt the rotation of the start-stop clutches 102 by engagement with the preliminary stop pins 104A, as illustrated in Fig. 6, to stop the clutch and shaft 99 in the pre-

liminary stop position. In this position, cams TL (Fig. 6) at both stations, permit contacts 224 and 225 to close (Fig. 6) thereby energizing the coil of the speed lock magnet SLM1 at station A, for example, by means of the following circuit: battery B1, coil of speed lock magnet SLM1, contacts 224 and 225, contacts 228 and 229 of relay SRR1 (now deenergized) the spacing contact S of line relay LR1, to ground. Upon release of key SRK2 at station B, the send-receive relay SRR1 at station A remains deenergized, but it is to be noted that line relay LR1 at station A is energized from station B which relay thereupon closes a circuit through the start stop magnet SSM1 to energize the same, so that the stop arm 103 at station A is attracted and clutch 102 is released for rotation until the normal stop pin 104B engages the stop arm 103 and the start-stop shaft 99 is rotated so that cam TL moves the contact 224 to a position mid-way between contacts 223 and 225 (Fig. 7) to thereby interrupt the circuit through the coil of SLM1 to release the speed lock arm controlled thereby, as described in the above mentioned copending application, so that the keyboard is released. As long as the operator at station B holds down the key SRK2, the operator at station A cannot transmit and is thereby warned that station B wishes to take over. When SRK2 is released, at station B, the operator at station B can transmit the message he desires to deliver. The "break in" is therefore immediate and positive and automatically reverses the direction of transmission to thereby save time in operation.

Signal light

A neon glow tube NL, as illustrated in Fig. 4, is incorporated into the teleprinter system to indicate to the operator the condition of his send-receive relay. When the neon tube glows, the operator is assumed that the relay at his station is in the send position and that the station is thereby prepared for sending. The circuit through the neon tube is established as follows: Upon depression of key SRK1, for example, a circuit is closed from battery B1, contacts 230, 231, since the send-receive relay SRR1 is energized, via the neon tube, marking contact M, armature of the line relay, to ground. During transmission of signals, it is to be noted, that the transfer of the tongue of relay LR1 from marking to spacing momentarily interrupts the continuous glow of the neon tube in accordance with the quality of the signal characteristics.

Sending

While the respective elements, comprising the sending and receiving system, and their specific operation, have been described in detail, a complete sending operation will now be briefly described in order to bring out the specific coordination among the several elements of the novel system in the transmission of a character representing code signal and a complete receiving operation will subsequently be briefly described.

After the station A, for example, has been conditioned for sending, by depression of the send-receive key SRK1 at station A and the send-receive relay SRR1 is energized and the start-stop shaft 99 is in the normal stop position with relay SSM1 energized and the stop arm 103, as illustrated in Fig. 4, depression of a chosen character key (Fig. 2) produces a setting of the permutation unit switches in accordance with the code value of the character, and the universal bail contacts

87UXa and 87UX are opened. Assuming that the permutation unit switches are positioned as illustrated in Fig. 4, the opening of the universal bail contacts deenergizes the circuit through these contacts to the send-receive relay SRR1 so that the line and the line relay LR1 are deenergized. The armature of the line relay moves from contact M to contact S, magnet SSM1 is deenergized, arm 103 is released and the normal stop pin 104B, being thereby released, the clutch 102 starts on its one complete revolution. Release of clutch 102 rotates the start-stop shaft 99 as described above in connection with Figs. 15 and 16, whereupon the cams TC, TL (Fig. 6), T1 to T6, inclusive, and TP are sequentially rotated to operate their respective switches TXC, TXL, TX1 to TX6, inclusive, and TXP (Fig. 7). Actuation of the contacts of switch TXC (Fig. 5) energizes the control relay CR1 to open the contacts 88 and 88a whereby SSM1 is removed from control of the line signals until the stop or marking line signal impulse is transmitted. The subsequent closure of the universal bail contacts, upon release of the character key, since contacts 88 and 88a are disengaged does not establish a circuit to the line. The code elements of the line signals, however, are controlled by the cams T1 to T6, inclusive. Cam TL (Fig. 6) closes the contacts 224 and 223 so that magnet SLM1 is energized to lock the keyboard so that no further keys can be depressed, until the particular permutation set up by depression of the chosen character key has been completed and the corresponding code signal has been transmitted to the line by a full revolution of the start-stop shaft 99 and the transmission cams T1 to T6, inclusive.

Since, under the conditions assumed as illustrated in Fig. 4, the permutation unit switch P1 is closed, closure of switch TX1 upon rotation of cam T1 places a marking condition upon the line by means of the following circuit: Battery B1, contacts 87 and 87a of permutation switch P1, contacts a and b of transmitting switch TX1, coil W of relay SRR1, switch blade of SRK1, contact 216, contacts 217 and 218 of the send-receive relay SRR1 (now energized) to the line, coil of the line relay LR1, which produces movement of its armature from the spacing to the marking contact M. It is to be noted, however, that the circuit through the start-stop magnet SSM1, is open at contacts 212 and 211 so that the line signal has no effect upon the start-stop magnet. The marking impulse continues from line relay LR1 over the line to the coil of line relay LR2 at station B (Fig. 3) to contacts 219 and 220 of the send-receive relay SRR2, to ground. The energization of relay LR2 produces movement of its armature from the contact S to the contact M which produces a receiving effect as will be described in detail later.

As the start-stop shaft 99 continues to rotate on its single complete revolution, the contacts a and b of the transmitting switch TX2, as controlled by cam T2, will be closed and since the permutation switch P2 is in the position, as illustrated in Fig. 4, a marking impulse is again transmitted over the line, as described in connection with permutation switch P1.

As indicated in Fig. 4, the permutation switch P3, is open, so that a spacing condition occurs on the line and the line relays LR1 and LR2 transfer their armatures from the contact M to the contact S. Since the start-stop magnet SSM1 at station A is no longer affected by the line relay LR1, the spacing signal transmitted through the

permutation switch P3 has no effect at station A. Upon receipt of the spacing impulse at station B, however, the line relay LR2 transfers its armature from engagement with contact M to engagement with contact S. As is seen in Fig. 7, shuttle magnet SM2 is in parallel with the start stop magnet SSM2 at station B and is affected by the received line conditions, as will be described in detail later.

As the start-stop shaft 99 continues to rotate, the particular character code signal set up by the permutation switches P1 to P6, inclusive, are transmitted to the line, by sequential closure of the cams T1 to T6, inclusive, which line conditions affect the line relay LR2 at station B, in accordance with the quality of the individual components, to thereby produce a receiving function characteristic of the particular character code combination, as will be explained in detail later.

After the cam T6 closes the contacts of switch TX6, the control cam TC closes the contacts 212 and 211 and opens the contacts 212 and 213 of switch TXC. Opening of contacts 213 and 211 deenergizes the coil of relay CR1, whereupon contacts 88 and 88a are closed, and since the contacts 87UXa and 87UX were previously closed upon release of the chosen character key, a stop or marking line signal of uniform duration, as determined indirectly by the rotation of the transmitting cams, is transmitted from battery B1, contacts 88, 88a, contacts 87UXa, 87UX, coil W of relay SRR1, switch blade of SRK1, contact 216, contacts 217, 218 of send-receive relay SRR1, through the coil of line relay LR1 at station A, over the line to the coil of line relay LR2 at station B, contacts 219 and 220 at station B to ground. Energization of line relay LR1 transfers its armature into engagement with contact M. Since the cam TC has closed the contacts 212 and 211, as described above, the start-stop magnet SSM1 is again controlled by the line conditions and a circuit is closed from battery B1, contacts 212, 211, magnet SSM1, contact M to ground, whereupon the magnet SSM1 is energized to attract its armature SSMA to rotate arm 103 into position to engage the stop pin 104B whereby the clutch 102 is stopped in its normal stop position after a signal complete revolution and the start-stop shaft 99 is also stopped in its normal stop position.

Also, subsequent to the closure of the contacts of switch TX6 by cam T6, the contacts of switch TXP (Fig. 7) are closed by the cam TP at station A. Such closure of contacts a, b, c and d of the switch TXP at station A produces no effect since the relay SRR1 is energized and contacts 230 and 232 (reverse of Fig. 7) are open and no circuit is closed through the line 233, line 233b, a key solenoid coil KS and part of the electrical translator, through this part of the electrical translator to line 234, contacts b and a of switch TXP to ground. Such a circuit is closed at the receive station B, as will be explained in connection with the description of the receiving function. The code signal permutation corresponding to the chosen depressed character key is therefore transmitted, as set out above, over the line to the receive station, and the single revolution clutch is released from the normal stop position and subsequently stopped at the normal stop position in position to transmit the next succeeding character code signal.

Receiving

Referring to Fig. 3, when station A is conditioned for sending, the send-receive relay SRR1

is energized and the start-stop clutch 102 is in the normal stop position with the start-stop magnet SSM1 energized. The line relays LR1 and LR2 are energized and their respective armatures are in engagement with the respective mark contacts M. The send-receive relay SRR2 is deenergized, as illustrated, and the start-stop clutch 102 at the receive station B is in the normal stop position and start-stop magnet SSM2 is energized.

Upon depression of a chosen character key at station A, with consequent opening of the universal bail contacts whereby the line is deenergized for the duration of a signal element period and the line relay armatures are moved from contact M to contact S, the magnet SSM1 at station A is deenergized, as explained above, and the stop arm 103 is released and start-stop clutch 102 is started on its one complete revolution.

Simultaneously, magnet SSM2 at station B is deenergized, the stop arm 103 at station B is released and its associated start-stop clutch is released for one complete revolution, simultaneously with the release and rotation of the start-stop clutch at station A. When station A has completed transmission of the start signal element and of the code selecting elements (six elements of code preceded by the start element); the universal bail contacts at station A, having been closed upon release of the depressed chosen character key, and control relay CR1 having been deenergized at the end of the last selecting element, by rotation of the start-stop shaft 99 carrying cam TC and thereby opening contacts 212 and 213, a stop or "marking" signal element was transmitted over the line, as described above, so that the armatures and line relays LR1 and LR2 are moved into engagement with their respective contacts M, magnets SSM1 and SSM2 are energized and the stop arms 103 at stations A and B are attracted so that the normal stop pin 104B engages the respective stop arms and the start-stop clutches at stations A and B are stopped at the end of a single revolution, in the normal stop position.

The start signal element and the stop signal element, namely, the No. 1 and No. 8 components of a full complete signal, serve therefore to maintain the start-stop shafts 99 at stations A and B in synchronism, while the line signal sequences are directly or indirectly controlled by the sending distributor, thereby assuring accurate timing of these sequences.

Since the start-stop shafts 99 at both stations are rotating in synchronism subsequent to the transmission of the No. 1 component of the full complete signal, the six selecting components of the signal can be utilized to sequentially affect elements at the receive station, in a predetermined time sequence, to thereby produce results characteristic of the particular quality of and disposition of the sequential components of the character representing code signal.

Referring to Fig. 7, it is noted that the send-receive relay SRR2 thereof is illustrated in a deenergized condition, which condition corresponds to a receiving condition (see also Fig. 3, station B). Before reception of the start or spacing component of a full complete signal, cam TL is in the position shown in Fig. 7 with contact 224 midway between contacts 223 and 225 and with contacts 222 and 221 out of engagement, the start-stop clutch being, as shown, in the normal start position. Were the start-stop clutch in the preliminary stop position, such as occurs when station B "breaks in" and the line is deenergized,

the clutch at station A would be in the preliminary stop position and cam TL would permit contact 224 to engage contact 225 and the speed lock magnet SLM1 at station A (Fig. 6) would be energized through a circuit extending through the armature of line relay LR1 in engagement with its contact S, as previously described.

However, at station B, as illustrated in Fig. 7, with send-receive magnet SRR2 deenergized and with the line energized and clutch 102 in the normal stop position, the circuit from battery B2, line 235, contacts 230, 232, line 233, line 233c, contacts 221 and 222 of switch TXL, line 236, shuttle-magnet SM2 (see also shuttle magnet SM of Figs. 15 and 16), line 237, contact M and armature of line relay LR2 to ground, is open at contacts 221 and 222 but it is to be particularly noted, that as soon as start-stop shaft 99 rotates from the normal stop position, cam TL closes the contacts 222 and 221, and the shuttle magnet SM2 is energized when the line is energized and is deenergized when the line is deenergized, by the circuit just traced above through the contacts 221 and 222, so that energization or non-energization of the shuttle magnet will set the tumblers ST1—ST6, respectively.

Likewise, when the send-receive relay SRR2 is deenergized or is in its receive condition, a circuit is partly closed from battery B2, line 235, contacts 230 and 232, line 233, line 233a to the cascade tongue 180 of the electrical translator, and the remainder of the circuit will be completed through the electrical translator tongues set in accordance with the operation of the tumblers ST1, ST2 and ST3 in accordance with the first three code signal selecting elements corresponding to the particular character key depressed at the sending station A, through a chosen group relay, line 238, one of the contacts d of either switches TX4, TX5, TX6 or TXP, contact c of one of these switches to ground. This circuit will be completed as soon as cam T4 closes the contacts of switch TX4 and the circuit is held closed by closure of switches TX5, TX6 and TXP sequentially.

Assuming that a complete signal, as diagrammatically represented in Fig. 21 is transmitted and that the permutation unit switches P1 to P6, inclusive at station A are positioned as illustrated in Fig. 4.

After the first spacing component of the full complete signal which is the start element and which releases the start-stop shafts of the two machines at the respective stations, the first selecting code element or the No. 2 element of the complete signal is transmitted from station A by means of the permutation unit switch P1 (Fig. 4) and since this selecting code element is a marking pulse (Fig. 21), the line is energized, as above described, and the armature of line relay LR2 (Fig. 7) is moved into engagement with contact M. This closes a circuit through the shuttle magnet SM2, to energize the same, and the shuttle 168 (Fig. 15) is moved so that an opening 169 in the shuttle is aligned with the tumbler ST1 (Fig. 22) so that the tumbler ST1, remains in its lower position, as previously described, and the cascade switch tongue 180 (Figs. 22 and 7) is left in engagement with contact 180a, as illustrated in Fig. 7. Likewise, the marking, spacing, spacing, marking, spacing pulses transmitted sequentially by the permutation switches P2 to P6, inclusive, at station A, selectively actuate or do not actuate switch tongue, 181 and its associated tongue 183 and its associated tongues, 187 and

its associated tongues, 191 and its associated tongue, and tongue 193, respectively, so that they are positioned, as shown in Fig. 7, so that the group relay GR2 is energized and the multiple contact switch tongue 239 thereof closes a circuit through an associated contact 239a and the chosen key-operating solenoid CKS.

The first three selecting code impulses of the signal, therefore, select the group relay by closure of the following circuit: from battery B2, line 235, contacts 230 and 232, line 233, line 233a, cascade switch tongue 180, contact 180a, tongue 181, contact 181a, tongue 183, contact 183b, through the coil of group relay GR2, line 238, and then as the cams T4, T5, T6 and TP close the contacts of switches TX4, TX5, TX6 and TXP, a circuit is closed sequentially through the respective contacts d, c of these switches to ground. The utilization of these holding circuits through the auxiliary holding contacts c, d of the switches TX4, TX5, TX6 and TXP avoid unnecessary sparking of the group relay cascade contacts. Were not the holding circuits through these auxiliary contacts utilized, one group relay, further, would always be energized, causing undesirable heating, and during the time intervals in which the No. 1, No. 2 and No. 3 selecting code signal elements were translated, the cascade tongues which were actuated in accordance with the particular code value would open a circuit and thereby produce unnecessary sparking. By the utilization of the holding circuit, as just described, the circuit through the cascade switches is not closed, until the first three selecting code signal elements have been translated and thereupon the proper group relay is held energized through the holding circuits closed through the auxiliary contacts c and d of the switches TX4, TX5, TX6 and TXP.

Similar to the closure of the circuit through the group relay GR2 as just described, a circuit is closed from the battery B2, line 235, contacts 230 and 232, line 233, line 233b, the multiple contact switch tongue 239 of group relay GR2, contact 239a, chosen key-solenoid CKS, corresponding to the character key represented by the particular code value of the chosen key depressed at station A, contact 189b, tongue 189, contact 192a, tongue 192, contact 193b, tongue 193, line 234, and when the cam TP closes the contacts of the switch TXP, the circuit is completed through contacts b, a, respectively, of switch TXP, to ground. It is to be noted that the holding circuit, as described above, is maintained closed until after the chosen key solenoid is energized through the action of the cam TP closing a circuit through that particular chosen key solenoid of the group relay selected by the first three selecting signal elements, which solenoid, it is to be noted, is selected by the No. 4, No. 5 and No. 6 components of the selecting code signal elements.

While the cams T4, T5, T6 and TP at the sending station A are sequentially operated during transmission, it is to be noted that no circuits are closed through the translator at the sending station A, since the contacts 230 and 232 (Fig. 4) of the send-receive relay SRR1 are maintained in open position.

While the cascade switch tongues of the electrical translator have been described as being sequentially operated when the cascade switch tongues are controlled by the novel selector, as illustrated in Figs. 15 and 17, it is to be particularly noted that when the novel selector of Figs. 24 and 25 is utilized, tumblers cooperating there-

with to set cascade switch tongues may produce sequential closing of the switch blades as described above, or the first, second and third, tumblers, namely, ST1, ST2 and ST3 may be simultaneously operated to select the group relay which is subsequently held energized by the holding circuits of switches TX4, TX5, TX6 and TXP and the tumblers ST4, ST5 and ST6 may be later simultaneously operated, just prior to the printing, as controlled by the cam TP and the contacts of switch TXP closing the circuit through the selected solenoid or, on the other hand, the six storage tumblers may be simultaneously operated to close all of the cascade switches, just prior to closure of the printing circuit, in which event the holding circuits are not required.

During the receiving operation, it is to be noted that the print contacts controlled by the cam TP, are opened just before the start-stop shaft is stopped by the stop pawl. Also during the eighth signal signal code element of the complete signal, the start-stop magnet SSM2 is switched into the local circuit in place of the shuttle magnet SM2, since the cam TC closes the contacts 212 and 211 of switch TXC while the cam TL opens the contacts 221 and 222 to thereby deenergize the shuttle magnet SM2.

Magnet SSM2 is therefore energized, in response to the received stop signal and holds the stop arm 103 in its attracted position to thereby engage the stop pin 104B of the start-stop clutch 102 to thereby stop the clutch and the start-stop shaft in the normal stop position awaiting the start signal component of the next transmission cycle.

Novel selector means are therefore provided comprising different embodiments thereof and a novel mechanical-electrical translator is likewise provided.

While there has been shown and described and pointed out the fundamental novel features of the invention as applied to a plurality of embodiments it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In combination, means producing a signal comprising a code permutation of a plurality of similar electrical signal components, each permutation being characteristic of a predetermined item, a control element, one for each predetermined item, a plurality of mechanical selector members, one for each signal component, a plurality of group relays, circuits controlled by said group relays for selecting said control elements in groups, a plurality of circuit closing elements arranged in a progression to produce successive halving of circuits selected and controlled selectively by certain of said mechanical selector members for selecting one of said group relays, in accordance with certain of the respective components of a certain code permutation, and a plurality of circuit closing elements arranged in a progression to produce successive halving of circuits selected and controlled selectively by the remaining mechanical selector elements in accordance with the remaining components for selecting a chosen one of the control elements of the selected group and in accordance with said

certain code permutation only, means sequentially controlled by said separate signal components, means for actuating said mechanical selector elements, and means controlled by said sequentially controlled means for selectively rendering said actuating means operative or inoperative in accordance with the respective signal components.

2. In combination, a keyboard of different characters, means controlled by the keys of said keyboard, respectively, for producing line signals having a chosen code permutation of signal components of one of two line conditions in accordance with the selected key character, means for sequentially transmitting said components, a plurality of solenoids, one for each key, for controlling the operation of said key in response to a particular permutation of the components of a received electrical signal, means for sequentially receiving the respective signal components of code permutations and selectively energizing one of said solenoids only, in accordance with the respective permutations, and comprising a relay, sequentially responsive to the respective components of said signal, tumbler means positioned in one position or another in accordance with the one or the other line condition, an electrical translator including a plurality of group relays, a group of contacts controlled by each group relay, respectively, and each of said contacts, respectively, controlling a circuit to a corresponding solenoid, a plurality of contacts controlled by certain of said tumblers, respectively, mounted to be selectively connected in cascade arrangements in variable permutations to select one of said group relays in accordance with respective permutations of said signal elements, which selectively position certain of said tumblers, and a second plurality of contacts controlled by certain others of said tumblers, mounted to be selectively connected in cascade arrangements in variable permutations, to select a certain one of the contacts of the selected group, whereby one solenoid only is selected in accordance with a code permutation of signal components corresponding to a chosen character.

3. Selector means controllable by received sequential code signal elements comprising a series of members, one for each element of code, means mounting said members for movement in two opposite directions longitudinally thereof, means synchronized with the sequential reception of the code signal elements for selectively actuating said members, means controlled by the reception of said code elements, cooperating with said members to determine the selective actuatable or non-actuatable condition of said members and comprising a reciprocable shuttle, operated in one direction or the other in accordance with the nature of a received code element, and a pivoted pawl, carried by each of said members and cooperating with said synchronizing means and with said shuttle means whereby said members are moved in one direction or the other, selectively, in accordance with the nature of a received code element.

4. Selector means controllable by received sequential code signal elements comprising a series of members, one for each element of code, means mounting said members for movement in two directions longitudinally thereof, means maintaining said members at the limit of movement in one direction and including a resilient biasing means, means for retaining said members at the limit of movement in the opposite direction and including resilient locking means, means piv-

totally mounted on each of said members and resiliently biased to one position, means, rotated in step with the sequential reception of code elements, for selectively actuating said pivotally mounted means, and means controlled by the reception of said code signal elements cooperating with said pivotally mounted means to produce selective actuation or non-actuation of said members by said rotated means, in accordance with the character of received code elements.

5. Selector means controllable by received sequential code signal elements comprising a series of members one for each element of code, means mounting said members for movement in two directions longitudinally thereof, means maintaining said members at the limit of movement in one direction and including a resilient biasing means, means for retaining said members at the limit of movement in the opposite direction and including resilient locking means, means pivotally mounted on each of said members and resiliently biased to one position, means rotated in step with the sequential reception of code elements for selectively actuating said pivotally mounted means and means controlled by the reception of said code signal elements cooperating with said pivotally mounted means to produce selective actuation or non-actuation of said members by said rotated means in accordance with the respective character of received code signal elements and means comprising a toothed shuttle reciprocable in one direction or the other to align or disalign the teeth thereof and said pivotally mounted members in accordance with the respective nature of received code elements.

6. Selector means controllable by received sequential code signal elements comprising a series of selecting members, one for each element of code, means mounting said members for movement longitudinally thereof, a cam shaft, a series of cams mounted on said shaft, respectively aligned with said members, the operating positions of said cams being respectively, sequentially, distributed circumferentially of said shaft, means for rotating said shaft in step with the sequence of received signal elements, a magnet, means sequentially energizing said magnet in accordance with the respective nature of sequentially received signal elements, a reciprocable, toothed shuttle, means resiliently mounting said shuttle in one biased position, means controlled by said magnet actuating said shuttle to an opposite position whereby the teeth of said shuttle are respectively aligned or disaligned with the several selector members in accordance with the respective nature of the code elements received.

7. Selector means controllable by received sequential code signal elements comprising a series of rotatable double-cam members, one for each element of code, means for rotating said members in step with received code signal elements, a separating wall between the respective single cams of each of said double-cam members, a series of selector members, one for each double-cam, and means controlled by received signal elements for selectively shifting said selector members from engagement with one of said single

cams to engagement with the paired single cam in accordance with the respective nature of the received elements.

8. Selector means controllable by received sequential code signal elements comprising a cam shaft, means for rotating said shaft in accordance with the received signal elements, a plurality of double-cam members mounted on said shaft for rotation therewith, means separating the respective single cams of said double-cam members, means circumferentially distributed about said separating means, respectively, and providing a passage in said separating means at differential sequential times during the rotation of said shaft, 15 a plurality of selector members, means mounting said selector members for engagement with said cams, respectively, and for oscillation about a chosen point, and means for oscillating said members in one direction or the other in dependence upon the nature of received signal elements, respectively, and in step therewith whereby said selector members are selectively passed from one of said single cams to the other of the pair in accordance with the respective nature of received signal elements.

9. Selector means controllable by received sequential elements comprising a rotatable shaft, a series of cams mounted for rotation with said shaft, means separating the operative surfaces of all pairs of adjacent cams, means providing a passage in said separating means, respectively, at different circumferential positions around said shaft, a plurality of selector members, means resiliently biasing said members, respectively, 30 against one or the other of said pairs of cams, a reciprocable shuttle, means for reciprocating said shuttle in accordance with received signal elements, converging slots formed on said shuttle, one for each of said members, means on each of 35 said members, respectively, for cooperating with opposite sides of said converging slots upon reciprocation of said shuttle, whereby said members are selectively passed through said passages in accordance with the nature of signal elements received.

10. Selector members controllable by received sequential code signal elements comprising a rotatable shaft, a series of pairs of cams mounted on said shaft, means providing a passage from the periphery of one cam to the periphery of the other of each pair, a drop on each of said cams, an operating element on every other cam, a plurality of selector members each comprising a slotted element, means for biasing said members, respectively, into engagement with one or the other of the pairs of cams, a shuttle, means selectively reciprocating said shuttle within the slots of said slotted elements and in step with received signal elements, oppositely directed transfer surfaces formed on said shuttle, one pair for each selector member, respectively, and means rotating said shaft in synchronism with received signal elements whereby the drops on said cams are sequentially aligned with said selector members, following the selective reciprocation of said shuttle.

HARRY J. NICHOLS.

CERTIFICATE OF CORRECTION.

Patent No. 2,315,727.

April 6, 1943.

HARRY J. NICHOLS.

It is hereby certified that error appears in the printed specification of the above numbered patent requiring correction as follows: Page 19, second column, line 27, claim 9, before the word "elements" insert --code signal--; and that the said Letters Patent should be read with this correction therein that the same may conform to the record of the case in the Patent Office.

Signed and sealed this 22nd day of June, A. D. 1943.

Henry Van Arsdale,
Acting Commissioner of Patents.

(Seal)
